Inventor:

Alfred J. Thomson,

by Walter E. Lombard
Atty.

UNITED STATES PATENT OFFICE.

ALFRED J. THOMSON, OF CANTON, MASSACHUSETTS.

CLAMP.

1,263,822.

Specification of Letters Patent. Patented Apr. 23, 1918.

Application filed March 22, 1917. Serial No. 157,048.

To all whom it may concern:

Be it known that I, ALFRED J. THOMSON, a citizen of the United States of America, and a resident of Canton, in the county of 5 Norfolk and Commonwealth of Massachusetts, have invented certain new and useful Improvements in Clamps, of which the following is a specification.

This invention relates to clamps for use in stretching hides and skins, the object being to provide a device of this character which is adapted to be used without perforating the edges of the hide or otherwise injuring the same.

10 To this end the main portion or body of the clamp is provided with a jaw at one end and has ears to the outer ends of which is pivoted one end of the clamping lever which is provided intermediate its ends with a 15 curved cam surface adapted to coact with said jaw and force the hide not only against said jaw but also against the under face of 20 the plate forming the body portion of the clamp.

25 The invention consists in certain novel features of construction and arrangement of parts which will be fully understood by reference to the description of the drawings and to the claims hereinafter given.

30 For the purpose of illustrating the invention one preferred form thereof is illustrated in the drawings, this form having been found to give satisfactory and reliable results, although it is to be understood that the various 35 instrumentalities of which the invention consists can be variously arranged and organized and that the invention is not limited to the precise arrangement and organization of these instrumentalities as herein shown 40 and described.

Of the drawings:

Figure 1 represents an elevation of a clamp embodying the principles of the present invention.

45 Fig. 2 represents an inverted plan of the same.

Fig. 3 represents a longitudinal section on line 3—3 on Fig. 2.

Fig. 4 represents an elevation of one end 50 of the same, and

Fig. 5 represents an elevation of the opposite end of the same.

Similar characters designate like parts throughout the several figures of the drawings.

55 In the drawings, the body portion of the

clamp consists of the plate 10 having a jaw 11 at one end and the downwardly and forwardly extending ears 12 on the opposite sides of said plate 10. The rear end of the 60 plate 10 is provided with an eyelet 13 through which is adapted to be secured one end of a cord the opposite end of which is adapted to be secured to the hide stretching frame.

65 The jaw 11 is inclined slightly toward the front of the plate 10 and has a sharp edge substantially in the plane of the under face of the plate 10, as shown in Fig. 1 of the drawings.

70 The outer ends of the ears 12 have cylindrical openings 14 extending therethrough into which project the pintles 15 on the end of the pivoted lever 16. Intermediate its ends the lever 16 is provided with a curved 75 cam surface 17 adapted to coact with the jaw 11 to grip the leather or skin 18 being stretched.

75 The lever 16 is also provided with a portion 18* which is substantially parallel with the plate 10 when the hide or skin 18 is being stretched. The other end 19 of the lever 16 is inclined away from the plate 10, as indicated in Figs. 1 and 3 of the drawings, thereby providing means whereby the lever 85 may be moved about the pivot 15 into its inoperative position.

80 By bending the plate 10 upwardly adjacent to the jaw 11, as indicated at 20, provision is made whereby the hide when stretched 90 is retained in a perfectly flat and horizontal position so that the liquid used to finish the hide or skin is prevented from settling in spots around the edges of said hide or skin.

95 This settling of the liquid in this manner is very objectionable, and often incurs additional labor in finishing the hide.

The portion 20 of the plate 10 is made somewhat yielding so that when the lever 16 is operated to clamp the material 18 between the jaw 11 and the curved portion 17, said portion 20 is adapted to yield to accommodate itself to various thicknesses of material. By providing the cam surface 17 to 105 the lever 16 intermediate its ends, a smooth surface is always brought into contact with the material and injury thereto is prevented.

110 It is obvious that the more strain that is brought upon the hide or skin 18 the greater will be the clamping effect between the cam portion 17 and jaw 11. The lever 16 is pro-

vided with lateral projections 17* adapted to engage the front face of the ears 12 and thereby limit the movement of the lever 16.

When it is moved about its pivot 15 away from the plate 10 to permit the insertion of the hide between the cam surface 17 and the jaw 11, it is obviously desirable to limit the movement of said lever, which is accomplished by the projections 17*.

- 10 The jaw 11 is slightly outside of a line perpendicular to the plate 10 and extending through the axis of the pivots 15. As a consequence of this location of the jaw 11 relatively to the pivots 15, it is obvious that considerable force must be applied to the end 19 of the lever 16 to move the cam surface 17 by the jaw 11, thereby making impossible any accidental displacement of said lever 16. It is obvious, therefore, that when 20 the lever 16 is moved about its pivots 15 in either direction the initial action of the cam surface 17 will be to more firmly clamp the material against the jaw 11.

This makes a very simple construction of 25 clamp for use in stretching hides and skins, which is inexpensive to manufacture and very effective in its operation.

It is believed that the operation and many 30 advantages of this invention will be fully understood from the foregoing description.

Having thus described my invention, I claim:

1. In a device of the class described, the combination of a plate having side ears extending downwardly therefrom with their outer ends separated from said plate and said plate being provided with an extension beyond the base of said ears terminating in a sharp edged jaw; and a lever pivotally 35 mounted at one end in said ears, said lever consisting of a plate formed between its pivots and its opposite end with a curved cam portion adapted to co-act with said jaw and so arranged that the strain on the 40 clamped material will cause said cam portion to more firmly clamp said material.

2. In a device of the class described, the combination of a plate having side ears extending downwardly therefrom with their outer ends separated from said plate and 45

said plate being provided with an extension beyond the base of said ears terminating in a sharp edged jaw, the edge of which is substantially in the plane of the under face of said plate; and a lever pivotally mounted 55 at one end in said ears, said lever consisting of a plate formed with a curved cam portion adapted to co-act with said jaw and so arranged that the strain on the clamped material will cause said cam portion to more firmly clamp said material.

3. In a device of the class described, the combination of a plate having side ears extending downwardly therefrom with their outer ends separated from said plate and 65 said plate being provided with an outwardly curved extension beyond the base of said ears terminating in a sharp edged jaw; and a lever pivotally mounted at one end in said ears, said lever consisting of a plate 70 formed with a curved cam portion adapted to co-act with said jaw and so arranged that the strain on the clamped material will cause said cam portion to more firmly clamp said material.

4. In a device of the class described, the combination of a plate having side members extending downwardly therefrom and provided with perforated ears projecting forwardly beyond the base of said side members and said plate also having a curved extension terminating in a sharp edged jaw substantially opposite the axes of the perforations in said ears; and a lever pivotally mounted at one end in said ears, said lever 80 consisting of a plate provided at one end with trunnions positioned in said perforations and having formed therein between its trunnions and the opposite end a curved cam portion an intermediate part of which is 85 adapted to co-act with said jaw and so arranged that the strain on the clamped material will cause said cam portion to more firmly clamp said material.

Signed by me at 4 Post Office Sq., Boston, 95 Mass., this 19th day of March, 1917.

ALFRED J. THOMSON.
